UNITED STATES PATENT OFFICE

ALAN C. CRAGO, DECEASED, LATE OF PITTSBURGH, PENNSYLVANIA, BY SAMUEL D. CRAGO, ADMINISTRATOR, OF PITTSBURGH, PENNSYLVANIA, ASSIGNOR TO WESTINGHOUSE ELECTRIC & MANUFACTURING COMPANY, A CORPORATION OF PENNSYLVANIA

CIRCUIT INTERRUPTER

Application filed August 29, 1927. Serial No. 216,033.

The invention relates to circuit interrupters and particularly to circuit interrupters which accomplish their purpose by forcing the arc incident to the opening of their contacts into a deionizing chamber, comprising means, such as a plurality of superposed metallic plates, which enables them to interrupt currents of large power.

While the invention is here shown as embodied in a circuit interrupter for alternating-current service and while particularly effective in such service, many of the principles of my invention are equally applicable to circuit interrupters for direct-current circuits.

One object of the invention is to provide means to assist in the extinguishing of the arc incident to the opening of the contacts of a circuit breaker by connecting a plurality of resistance elements in shunt and in series to the said arc, thereby facilitating its extinction.

Another object to the invention is to provide an arrangement wherein a single deionizing chamber is used with a plurality of resistance elements to successively extinguish the arcs incident to their use in interrupting a circuit in the manner above described.

A further object of the invention is to provide a means wherein a single deionizing chamber is used to interrupt the flow of energy in an electric circuit in several successive steps or stages.

Other objects of the invention will become apparent through reading the following specification taken in connection with the drawing in which:

Figure 1 is a side view of a circuit interrupter embodying the invention,

Fig. 2 is a detail view of a deionizing metallic plate embodied in the deionizing chamber of one form which may be utilized in connection with the invention, and

Figs. 3 to 7, inclusive, are illustrative diagrams showing the circuit connections of the resistance elements at various points in the course of operation of the circuit breaker.

Patent No. 1,784,760 and No. 1,819,207 issued, respectively, on December 9, 1930 and

August 18, 1931, show arrangements in which

the arc incident to the opening of circuit breakers in air is forced into a deionizing chamber and therein extinguished at the zero point of an alternating-current wave. By the employment of such deionizing chambers, it is possible to interrupt currents of large value in circuits of high voltage which hitherto have only been broken by the use of oil or other arc-quenching mediums. In connection with the extinguishing of arcs and such deionizing structures, it has been found that the amount of current which can be interrupted may be increased if resistances of suitable values are connected in shunt to the contacts when they first open and are later connected in series therewith. The arc is, so to speak, interrupted in two or more stages instead of at a single stroke.

It has also been found desirable to interrupt such an arc in more than two stages by providing a plurality of resistance sections of different values. The section of smallest resistance is connected in shunt to the arcing contacts when they first open and acts to assist the deionizing chamber in extinguishing the arc. It would be possible to furnish a deionizing chamber for each section of resistance used in extinguishing the arc but, since the structure of such chambers is relatively expensive, it is seen that expense may be saved through an arrangement in which a single deionizing chamber coacts with the first section of resistance to extinguish the arc in shunt thereto, and is then switched to extinguish the arc in the second resistor section; and so on, for all the resistor sections used.

A specific arrangement by means of which it is here proposed to accomplish this general result shows a circuit breaker comprising main contacts 1 and 2 and a bridging member 3 of conventional type. When the circuit breaker is actuated to its open position, the arm 4 supporting the bridge member 3 moves about its hinge 5 to the right, separating the bridging member 3 from the main contacts. It is usually desirable to provide, in addition to the bridging member 3, an arcing contact 6 which breaks its contact later than the

main contactor. Such auxiliary contacts are well known in the art.

The upper end of the arm 4 supports an arcuate member 7 faced with a suitable insulator 8 upon which are positioned, at intervals, a series of metallic blocks 9, 10, 11 and 12. The contact blocks are connected by any suitable means, such as flexible connectors 13, to a variable resistor 14 of any suitable type. The upper faces of the blocks 9, 10, 11 and 12 are machined to be concentric with the hinge 5. Above the single arm 4 is positioned, the deionizing chamber 15 which comprises a pair of metallic end-plates 16 and 17 faced on each side by insulating plates to form an enclosure which is open at the top. This chamber has, at its bottom end, a pair of arcing horns 18 and 19, the first mentioned of which may be referred to as a principal contact against the lower faces of which the contact blocks 9, 10, 11 and 12, aforesaid, make a moving engagement. The lower part of the deionizing chamber 15 is empty but in its upper portion are located a series of spaced vertical metallic plates of the form shown in detail in Fig. 7. The plates may be of copper, $\frac{1}{16}$ of an inch thick and spaced apart $\frac{1}{16}$ of an inch by a series of washers of fish paper or other suitable insulation. The lower edges of the metallic plates are provided with notches of substantially V-shape, as shown in Fig. 2, which align when the plates are assembled in the deionizing chamber to form a V-shaped groove which greatly increases the efficiency of the chamber in extinguishing arcs.

The lower portions of the insulating side plates of the deionizing chamber above mentioned are held tightly between the poles of a blowout magnet 21 comprising an iron yoke 22 and an exciting winding 23 therefor. One end of the blowout-magnet winding is connected to the contact terminal 1 and the other end is connected to one of the end plates 16. The other end plate 16 is connected, through arm 4 and conductor 25, to the other main contact 2. An inspection of the drawing will show that the blowout magnet and the deionizing chamber 15 are thereby connected in series across the main contacts 1 and 2.

The deionizing chamber above described is not part of the present invention but forms the subject matter of the Slepian Patent 1,784,760 above mentioned. Such being the general structure of the present circuit breaker, its mode of operation in opening the circuit will now be described.

When the main bridging member 3 and the auxiliary contact 6 open the circuit between the main contacts 1 and 2, contact member 9 is so positioned as to bridge the arcing horns 19 and 18. The opening of the bridge across members 1 and 2, however, forces current to flow through the winding

23 of the blowout magnet to the end plate 16 and then through the arcing horn 18, contact member 9, arm 4 and conductor 25 to the other contact 2. Fig. 3 diagrammatically illustrates this stage of operation.

A slight additional movement of the arm 4 breaks contact between the block 9 and the arcing horn 18 and draws an arc therebetween. This arc is shunted by the first section 27 of the resistor 14, since the contact block 10 is so positioned that it makes contact with the arcing horn 18. A further movement of the arm 4 to the right, transfers the right-hand terminal of the arc from the member 9 to the other arcing horn 19. The blowout magnet 21 then drives this arc upward into the deionizing structure comprising the superposed plates and forces it into the V-shaped groove therein. As the current in this arc falls to zero in the course of the alternating-current cycle the arc path is rapidly deionized because of the contiguity of the metallic plates which tend to discharge any ions which may impinge upon them. When, in the course of the succeeding alternating-current wave, the voltage between the end plates 16 rises, what few ions remain free in the arc path are drawn into contact with the deionizing plates and are discharged also. In consequence, the electric force is insufficient to reestablish an appreciative flow of current through the arc path, and the arc remains extinct after the end of the first half cycle of the alternating current. Fig. 4 represents this operative position of my interrupter. The foregoing steps, however, leave a certain amount of current flowing through the resistor section 27. A further movement of the arm 4 to the right breaks contact between the contact block 10 and the arc horn 18 and establishes an arc therebetween shunted by the resistor section 28. This process, it will be seen, is precisely like that which occurred on the breaking contact of contact block 9 and arc horn 18 except that resistor section 27 is now in series with the main circuit. As a consequence of this later condition, the value to which the current can rise in the alternating half wave is strictly limited.

A further movement of the arm 4 transfers the arc to the other arcing horn 19, and the blowout magnet 22 forces it up into the deionizing structure where it is extinguished in its turn. Fig. 5 represents the circuit connections at this stage of the operation. A further movement of the arm 4 then breaks contact between the block 11 and the arc horn 18, shunting the arc therebetween by the resistor section 29 and placing resistor sections 27 and 28 in series with the main line to further limit the rise of current, as shown diagrammatically in Fig. 6. The arc between members 18 and 11 is extinguished precisely in the manner which has been described be-

fore and, finally, a contact block 12 draws an arc from the arc horn 18, which is shunted by no resistance, but which is so limited by the resistor sections 27, 28 and 29, which are now

5 connected in series with the main line, as indicated in Fig. 7, that the deionizing structure is capable of completely interrupting current flow in the circuit.

Accordingly, there has been provided 10 means by which a single deionizing chamber can be made to interrupt the arc formed by insertion of a plurality of resistance sections in series with a circuit in which it is described to interrupt current flow, thereby 15 making possible the interruption of larger amounts of power than would be possible were the circuit to be interrupted at a single operation.

While the present invention has been described as used in connection with specific devices, it will be obvious that it is not limited to such use but is of general applicaiton to effect circuit interruption even when special means are provided to extinguish the arcs 25 incident to separation of the contacts.

The principles which are embodied in the circuit breaker herein described are applicable to, and may be utilized for, many other processes which will be apparent to those 30 skilled in the art without departure from the scope of the invention. Accordingly, it is desired that the claims herein shall be given the broadest interpretation consistent with the limitations expressed therein and with 35 those imposed by prior art.

What is claimed is:

1. In a circuit interrupter a principal contact, a movable contact adapted to draw an arc from said principal contact and to 40 connect an impedance in shunt to said arc, means to transfer a terminal of said arc from said movable contact to an electrode contiguous to means to extinguish said arc, means to remove said movable contact from the 45 vicinity of said arc extinguishing means, a second movable contact adapted to draw an arc in series with said impedance from said principal contact and in contiguity to said arc extinguishing means.

50 2. In a circuit interrupter, a pair of arc terminal members, means to establish an arc, means for transferring said arc to said pair of arc terminal members, means for connecting a resistance in shunt with said arc, means 55 for drawing a second arc in series with said resistance and means for transferring said second arc to said pair of arc terminal members.

3. In a circuit interrupter, means for de- 60 ionizing an arc including a pair of arc terminal members, separable contacts for drawing an arc, means for transferring said arc to said pair of arc terminal members, means for connecting a resistance in shunt with said 65 arc, means for drawing a second arc in series

with said resistance and means for transferring said second arc to said pair of arc terminal members.

4. In a circuit interrupter, means for drawing an arc, means for shunting said arc by a resistance, means for deionizing an arc including a pair of arc terminal members, means for transferring said arc from said arc drawing means to said terminal members, and means for drawing a second arc after the 70 extinction of said first arc, means for shunting said second arc with a higher resistance than said first arc, and means for transferring said second arc to said pair of arc terminal members to be extinguished by said 75 deionizing means.

5. In a circuit interrupter, means for drawing an arc, means for shunting said arc by a resistance, means for deionizing an arc including a pair of arc terminal members, means for transferring said arc from said arc drawing means to said terminal members, and means for drawing a second arc after the 80 extinction of said first arc, means for shunting said second arc with a higher resistance than said first arc, and means for transferring said second arc to said pair of arc terminal members to be extinguished by said 85 deionizing means.

6. In a circuit interrupter, means for drawing an arc, means for shunting said arc by a 90 resistance, means for deionizing an arc including a pair of arc terminal members, means for transferring said arc from said arc drawing means to said terminal members, and means for drawing a second arc after the 95 extinction of said first arc, said second arc being drawn in shunt with a resistance higher than that across said first arc, and in series with a current limiting resistance, and means for transferring said second arc to said pair of arc terminal members to be extinguished by 100 said deionizing means.

7. In a circuit interrupter, means for drawing an arc, means for shunting said arc by a 105 resistance, means for deionizing an arc including a pair of arc terminal members, means for transferring said arc from said arc drawing means to said terminal members, and means for drawing a second arc after the extinction of said first arc, means for shunting said second arc with a higher resistance than said first arc, means for transferring said second arc to said pair of arc terminal members to be extinguished by said 110 deionizing means, and means for moving both of said arcs on 115 said terminal members.

8. In a circuit interrupter, a pair of arc terminal members, a principal contact connected to one of said arc terminal members, a movable contact for drawing an arc from said principal contact and making contact with the other of said arc terminal members to transfer the arc thereto, a second movable contact for drawing another arc from said principal contact and making contact with 125 120 130

said other arc terminal member to transfer the arc thereto, said movable contacts having a resistance connected therebetween.

9. In a circuit interrupter, a pair of arc terminal members, a principal contact connected to one of said arc terminal members, a plurality of movable contacts, means for moving said contacts from said principal contact to draw a series of arcs therefrom and to make contact with the other of said arc terminal members and transfer said arcs thereto, said movable contacts having resistances connected therebetween so as to shunt each of the arcs as they are drawn.
10. In a circuit interrupter, a pair of arc terminal members, a principal contact connected to one of said arc terminal members, a plurality of movable contacts, means for moving said contacts from said principal contact to draw a series of arcs therefrom and to make contact with the other of said arc terminal members and transfer said arcs thereto, said movable contacts having resistances connected therebetween so as to shunt each of the arcs as they are drawn.
15. 10. In a circuit interrupter, a pair of arc terminal members, a principal contact connected to one of said arc terminal members, a plurality of movable contacts, means for moving said contacts from said principal contact to draw a series of arcs therefrom and to make contact with the other of said arc terminal members and transfer said arcs thereto, said movable contacts having resistances connected therebetween so as to shunt each of the arcs as they are drawn, each of said resistances having a higher value than the resistance shunting the preceding pair of contacts.

11. In a circuit interrupter, a pair of arc terminal members, a principal contact connected to one of said arc terminal members, a plurality of movable contacts, means for moving said contacts from said principal contact to draw a series of arcs therefrom and to make contact with the other of said arc terminal members and transfer said arcs thereto, said movable contacts having resistances connected therebetween so as to shunt each of the arcs as they are drawn and to be in series with the arcs drawn by the following movable contacts, each of said resistances having a higher value than the resistance shunting the preceding pair of contacts.

In testimony whereof, I have hereunto subscribed my name this 18th day of August, 45 1927.

SAMUEL D. CRAGO,
Administrator of the Estate of Alan G.
Craco, Deceased.
